CONCRETE BURIAL VAULT CLOSURE

Leonard E. Abbott, Kalamazoo, Mich.

Application November 1, 1947, Serial No. 142,262

Term of patent 14 years

(Cl. D19—1)

To all whom it may concern:

Be it known that I, Leonard E. Abbott, a citizen of the United States of America, residing at Kalamazoo, in the county of Kalamazoo and State of Michigan, have invented a new, original, and ornamental Design for a Concrete Burial Vault Closure, of which the following is a specification, reference being had to the accompanying drawing, forming part thereof.

Referring to the drawing:

Figure 1 is a perspective view of the concrete burial vault closure, showing my novel design;

Figure 2 is a top plan view of the closure shown in Figure 1;

Figure 3 is a side elevational view of the closure, and

Figure 4 is an end elevational view thereof.

I claim:

The ornamental design for a concrete burial vault closure, as shown.

LEONARD E. ABBOTT.
